UNITED STATES PATENT OFFICE

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE

TYPEWRITING MACHINE

Application filed July 18, 1927, Serial No. 205,313. Renewed July 26, 1928.

This invention relates to devices for feeding loose webs from stationary rolls to the traveling carriages of typewriters, and is illustrated as an attachment to the standard Underwood machine.

The web is fed from a stationary supply-roll beneath the rear of the machine upwardly onto the usual rearward extension provided on the transversely-operating carriage, to be conducted forwardly thereon to the platen proper.

With standard constructions, line-spacing is effected at the beginning of the carriage-return stroke, whereby a sudden pull is exerted upon the web. The opposing inertia of the heavy supply-roll tends to set up a comparatively high tension in the web, which, on account of the extreme left-hand displacement of the carriage at this time, unequally stresses the web, tending to rupture its side edge, or else causes irregular line-space, due to slippage of the web upon the platen.

A feature of the invention is a lifter-frame swingably attached to the rear of said carriage-extension, and governed by the carriage movement to produce slack in the web for unrestricted line-space operation, and having an equalizer-bar which is itself swinged upon the swing-frame, so as to uniformly engage and tension the web throughout the width thereof, and to eliminate local strain upon the paper when lifting the same.

Other features and advantages will hereinafter appear.

In the accompanying drawings,

Figure 1 is a side elevation, partly sectioned, showing parts of a standard manion-folding machine and machine-stand engaged in web-feeding operation, the source of web-supply being shown as a roll of multiple-ply stationery.

Figure 2 is a perspective view of the rear part of the machine, showing details of the paper-feeding device including the novel equalizer-bar, the web being indicated in dot and dash.

Figure 3 is a detail view, showing the swivel connection between the equalizer-bar and the lifter-frame.

The web in Figure 1 is supplied from a roll 10 in three superimposed plies 11, 12 and 13. By means of a reel 14 the roll is rotatably mounted upon brackets 15, which are fast to the lower part of the rear legs 55 of the usual machine-stand. The web-plies from the supply-roll are led upwardly in back of the machine and over a guide-bar 17 onto a frame indicated, as a whole, by the numeral 18, and which rearwardly extends from the platen-carriage 19, and is formed with longitudinal rods 20 and 20^a and cross-rods 21 and 22 and by links 23 rigidly connected to the platen-carriage 19. The guide-bar 17, by means of mountings 24, is rigidly secured upon the rear cross-rod 21 of frame 18 and carries side gages 25 to laterally guide the web thereon. Passing over the frame 18 and the usual carbon-carriage 26 thereupon, the web-plies are interleaved with carbons 27 held on the carbon-carriage by the usual carbon-holding blades 27^a. The composite web is then advanced over guide-arm 28 and gripped by feed-rolls 29 to be fed around a platen 30, where a type-bar 31 indicates the printing. The leading edge of the web is shown as having reached a paper-gage 32 mounted upon a paper-table 33 of the platen-carriage. At 34 is indicated in dot and dash the usual lever for combined carriage-return and line-spacing operation; also in dot and dash is shown an operating handle 35 of the carbon-carriage. The platen-carriage is supported for transverse movement upon the machine by 75 a rail-member 36 secured to the usual type-writer-frame 37, while said frame 18, extending rearwardly from the carriage, is traveling upon a corresponding rail 38 by means of rollers 39, which are mounted upon 80 rigid brackets 40 depending from the frame-members 20 and 20^a. The part 41 of the brackets engages the rail 38 opposite the roller and is to keep said roller from lifting clear off the rail 38. The rail in turn is rigidly mounted upon rearward extensions 42 provided on the typewriter-frame 37 at either side thereof.

The web-loosener device mainly consists of a carrier-swing-frame 43 at the rear of 100

the machine and includes flat-bar side members 44 and 45 at their upper ends 46 and 47 respectively detachably hinged to the cross-rod 21 of said carriage-extension, and 5 at their lower ends joined together and riveted, as shown in the drawings, thereby forming a central projection 48 serving as a central support for the novel equalizer-bar 49 swiveled thereon and which is to lift 10 the web. A detail of the swivel joint in Figure 3 shows the projection 48 extending within a longitudinal slot 50 of the equalizer-bar 49 and pivoted thereto at 51.

The side members 44 and 45 of the carrier-swing-frame are spaced by a rod 52 upon which a bracket 53 by means of ears 54 is pivoted for vertical swinging movement, while simultaneously secured against lateral dislocation as it appears from the 20 drawings. The bracket carries a roller 55 to co-operate with a V-shaped rail 56, which is detachably secured at either end to the rearward extensions 42 of the machine-frame, each end 57 of said rail being bent 25 forwardly and by means of set-screw 58 rigidly held in a block 58^a, which, in turn, by means of a clip 59, is secured to the end of extension 42 of the machine-frame. This method of fastening the rail as well as the 30 hinging of the carrier-swing-frame described before permits a ready attachment of the web-feeding device to standard machines.

It will be understood that every time the 35 carriage passes in one direction, due to the roller 55 being forced over the V-shaped rail 56, the carrier-swing-frame will be pushed outwardly, so that the novel equalizer-bar thereupon uniformly adapting itself to the web may lift the same smoothly and cause the supply-roll to unwind accordingly.

In the operation of the machine unwinding will occur during the carriage-return 45 stroke, inasmuch as part of the slackened web is used up for line-spacing at the very beginning of the stroke, while in the further course thereof new slack is produced by the lifting device to accommodate the next 50 line-spacing operation.

It is clear as appears from Figure 1 that the novel equalizer-bar is of particular importance where the web-feeding pull from the platen is transmitted only through the 55 outer ply of a multiple-ply wound supply-roll herein illustrated.

This leading ply stationary at one end and transversely traveling at the other end and therefore particularly susceptible to strains 60 and ruptures cannot be overstressed with the intermediate novel self-adjusting lifter-bar, for obviously the bar skews with the ply as the upper portion thereof travels with the carriage, so that the pressure of the 75 bar is uniformly distributed across the bar-

engaged portion of the ply as the roll is 70 unwound by the movement of the loosening device as a whole. In the operation of manually pulling the leading end of the multiple-ply web forwardly over the carbon-carriage to arrange a section in position for 75 typing thereon, the bar is effective to tension the pressed portion of the outer ply uniformly throughout the forward feed movement of the multiple-ply web. By thus equalizing the stress in the bar-engaged portion of the paper not only is the web 80 itself protected against rupture, but also its excessive back strain upon the platen is easily eliminated, while on the other end the unwinding pull upon the supply-roll is exerted more effectively, thus promoting smooth operation of the machine as a whole.

Variations may be resorted to within the 85 scope of the invention, and portions of the improvements may be used without others.

Having thus described my invention, I claim:

1. In a continuous billing machine, the 90 combination with a web-feeding platen, a carriage therefor, a multiple-ply web supplied at the rear of the machine from a suitable source adjacent to the machine, and a frame rigidly attached to the rear of the carriage for web-intake and conducting the web to the platen, of a web-lifting device to facilitate feeding of the web, including an equalizer-bar extending across said web and located between the source of web-supply and the web-intake, said equalizer-bar centrally swiveled so as to fit itself to uniformly engage the web, and means to support said bar and which are reciprocatively actuatable to engage the same for web lifting and slackening operation. 95

2. In a continuous billing machine, the combination with a web-feeding platen, a carriage therefor, a multiple-ply web supplied at the rear of the machine from a stationary roll or spool mounted beneath the machine, whereby the outer ply is leading in unwinding said spool, and a frame rigidly attached to the rear of the carriage for web-intake and conducting the web to the platen, of a web-lifting device to facilitate feeding of the 100 web, including an equalizer-bar extending across said web between the source of web-supply and the web-intake, said equalizer-bar to be centrally swiveled so as to fit itself to uniformly engage the leading outer ply of the web, and means to support said equalizer-bar and which are reciprocatively actuatable to engage the bar for web lifting and slackening operation. 105

3. In a continuous billing machine, the 110 combination with a web-feeding platen, a carriage therefor, a multiple-ply web supplied at the rear of the machine from a stationary roll or rolls mounted beneath the machine, and a frame rigidly attached to 115

the rear of the carriage for web-intake and conducting the web to the platen, of a web-lifting device to facilitate feeding of the web, including an equalizer-bar extending across said web between the source of web-supply and the web-intake, said equalizer-bar to be centrally swiveled so as to fit itself to uniformly engage the web, and means to support said bar and which are reciprocatively actuatable to engage the same for web lifting and slackening operation, whereby said reciprocative movement is governed by the carriage movement to cause periodical unwinding of the supply-roll ahead of the line-spacing operation.

4. In a continuous billing typewriting machine, the combination with a web-feeding platen, a carriage therefor, a multiple-ply web supplied at the rear of the machine from a suitable source adjacent to the machine, and a frame attached to the rear of the carriage for web-intake and conducting the web to the platen, of a web-lifting device to facilitate feeding of the web, including an equalizer-bar extending across said web between the source of web-supply and the web-intake, said equalizer-bar to be centrally swiveled so as to fit itself to uniformly engage the web, a swing-frame at its lower end carrying said swiveled equalizer-bar and at its upper end pivotally engaged to the rear of the carriage-frame, so as to be swung in a vertical plane, a substantially V-shaped guide-rail or cam-member rigidly secured to the machine-frame, and a bracket upon said swing-frame also swingable in a vertical plane and carrying a roller to be operatively engaged with said guide-rail, so that when the carriage is transversely reciprocated, the roller is moved over the guide-rail and passing over the peak thereof will cause the frame to swing accordingly to engage the equalizer-bar thereon for periodical web lifting and slackening operation.

5. In a continuous billing typewriting machine having means supporting a stationary web-supply roll, the combination with a carriage engaging the leading end portion of a web paying off said roll, of a web-loosener including a web-engaging equalizer bar extending across the web adjacent the roll, a vibrating carrier mounted for movement with the carriage, and a pivotal connection between the carrier and the bar intermediate the ends of the bar to enable the carrier to press the bar against the web delivered from the roll, and to allow the bar to skew with the web as the upper portion of the web travels with the carriage, whereby the bar is effective to tension the pressed portion of the web uniformly throughout web-loosening.

6. In a continuous billing typewriting machine having means supporting a stationary web-supply roll, the combination with a

carriage engaging the leading end portion of a web paying off said roll, of a web-loosener including a web-engaging equalizer bar extending across the front face of the web adjacent the roll, a carrier swingably mounted for movement with the carriage, and a pivotal connection between the carrier and the central portion of the bar to enable the carrier to press the bar against the web delivered from the roll, and to allow the bar to skew with the web as the upper portion thereof travels with the carriage, whereby the bar is effective to tension the pressed portion of the web uniformly throughout web-loosening.

7. In a continuous billing typewriting machine having means supporting a stationary web-supply roll, the combination with a carriage engaging the leading end portion of a web paying off said roll, of a web-loosener including a web-engaging equalizer bar extending across the web adjacent the roll, a vibrating carrier mounted for movement with the carriage and extending downwardly from the rear of the carriage in front of the web, and a yieldable connection between the carrier and the central portion of the bar to enable the carrier to press the bar against the web delivered from the roll, and to allow the bar to skew with the web as the upper portion thereof travels with the carriage, whereby the bar is effective to tension the pressed portion of the web uniformly throughout web-loosening.

8. In a continuous billing typewriting machine having means supporting a stationary web-supply roll, the combination with a carriage engaging the leading end portion of a web paying off said roll, of a web-loosener including a web-engaging equalizer bar extending across the web adjacent the roll, a vibrating carrier mounted for movement with the carriage and having a downwardly and rearwardly directed offset portion disposed between the carriage and the web, and a yieldable connection between said offset portion and the bar to enable the carrier to press the bar against the web delivered from the roll, and to allow the bar to skew with the web as the upper portion of the web travels with the carriage, whereby the bar is effective to tension the pressed portion of the web uniformly throughout web-loosening.

9. In a continuous billing typewriting machine having means supporting a stationary web-supply roll, the combination with a carriage and line-spacing mechanism mounted upon said carriage and including a platen engaging the leading end portion of a web paying off said roll, of a web-loosener including a web-engaging equalizer bar extending across the web adjacent the roll, a vibrating carrier mounted for movement with the carriage, and a pivotal con-

nection between the carrier and the bar between its ends to enable the carrier to press the bar against the web delivered from the roll, and to allow the bar to skew with the web as the upper portion of the web travels with the carriage, whereby the bar is effective to tension the pressed portion of the web uniformly throughout web-loosening, and is further effective to tension said pressed portion uniformly as the web is fed to the platen by the line-spacing mechanism.
